UNITED STATES PATENT OFFICE

RICHARD LEMAIRE, OF SOLINGEN, GERMANY

HAIR-WAVING APPLIANCE

Application filed September 12, 1929, Serial No. 392,211, and in Germany November 3, 1928.

This invention relates to an appliance for effecting permanent hair waving by means of steam, and its object is principally to provide means for restricting the formation of 5 water condensation and for rendering such water harmless as happens to leak through.

This object is achieved according to the invention by providing a spherical water retainer in the pipe which connects the steam 10 generator with the steam distributing chest, and forming the latter with a gutter adapted to catch the drip from the valves; by providing clamping plates which form a tight seal with the hair as well as with the hair 15 steaming sleeve; and by providing, between the clamping plates and the head, an insulating plate provided with means for retaining any water that happens to leak through from between the clamping plates.

20 Fig. 1 of the accompanying drawings represents a diagrammatic view of the steam generator and the steam distributing chest, the latter being shown in section on the line I—I of Fig. 2,

25 Fig. 2 is a top view of the arrangement, Fig. 3 is a view on an enlarged scale of one of the hair wavers,

Fig. 4 is a view on a still further enlarged scale of one of the hair coiling rods,

30 Fig. 5 is a rear view of a pair of clamping plates in closed position,

Fig. 6 is a view showing the plates open,

Fig. 7 is a section on the line VII—VII of Fig. 5,

35 Fig. 8 is a view of a rubber cover for the clamping plates,

Fig. 9 is a section on the line IX—IX of Fig. 8,

Fig. 10 is a view of a head protecting plate,

40 Fig. 11 is a section on the line XI—XI of Fig. 10,

Fig. 12 is a view of a head protecting plate of different construction, and

45 Fig. 13 is a section on the line XIII—XIII of Fig. 12.

The hair waving appliance comprises a steam generator 1 which is heated electrically and which feeds the steam in the first place into a steam distributing chest 9. The 50 pipe 5 which connects the generator with the

chest is formed with abrupt bends so as to prevent water which is thrown up by the generator from being conveyed into the horizontal portion 5''. For the same purpose the upright portion 5' is fitted with a spherical 55 enlargement 6 wherein the water will in the first place be retained. The steam supply to the chest is regulated by means of a valve 7. A manometer 8 is provided, and the generator has an inlet funnel 3 for the water 60 as well as a water gauge 4. 2 is a switch or rheostat whereby the current supply is regulated.

The steam chest 9 is flat and cylindrical. It has a domed top plate and a steam inlet situated centrally in said plate. The steam outlets 11 are situated on the circumference of the chest and are uniformly spaced. Each outlet is fitted with a regulating valve 12. Drips from the latter are caught in a gutter 70 14 which is formed by an extension of the bottom plate 13 of the chest. A pipe rising from each outlet is bent over at 16 and carried thence downwards past the edge of the gutter for connection to a hair waver. This 75 connection is effected by means of flexible pipes 17. An electric steam superheater 15 is connected to the bottom plate of the chest 9.

Each hair waver comprises a pair of 80 clamping plates 22 and 23 which are hinged together at 24 and adapted to clamp a hair strand between their abutting edges 35, the latter being slightly concave as shown in Figs. 5 and 6. A lever clasp 25, which is pivoted at 26 to one plate, has a link 27 which is applied to a hook 28 on the other plate for clamping the two plates together about the hair strand. Segmental shells 36 and 37 are connected to the plate, one to each, so as to 85 form together a neck adapted to embrace the hair strand. One segment is extended so that the ends 40 project beyond the edge of the plate and form a fork wherein the hair strand can be easily assembled. The projecting ends of the segment overlap the mating plate and also its segment which is correspondingly shortened. U-shaped rubber or like covers 29 are slipped over the abutting edges of the plates so as to close resiliently 90 100

round the hair strand and form a tight seal. The two members 30 and 31 of the cover are preferably extended so as to cover the entire sides of the plate. One of the members is 5 formed with an arcuate slit for the reception of the neck segment, and the semi-circular flap 32 thus formed is held in position by a flange 33 formed at the inside of the segment.

The neck formed by the segments 36 and 10 37 serves for connection to a hair steaming sleeve 18, a flexible ring 39 of rubber or the like being slipped over a flange 38 on the neck and over the end of the sleeve. The latter carries a branch pipe 19 for connection to one 15 of the steam supply pipes 17, the steam being discharged from the sleeve through an aperture 20. The free end of the sleeve is closed and formed with a spherical enlargement 21 wherein water of condensation is retained. 20 The hair is coiled in known manner round a sleeve 43 which is mounted rotatably on a rod 41. The latter is fitted with a forked head 47 where it is hinged to a bracket 48 on one 25 of the clamping plates within the neck so that the rod and sleeve 43 can be enclosed together with the hair in the steaming sleeve 18. A screw threaded portion 44 at the free end of the rod carries a nut 45 whereby the sleeve 43 can be secured after the coiling of 30 the hair. The outer end of the rod is upset so as to form a head 50 which prevents the nut 45 from leaving the rod.

Between the clamping plates and the head an insulating plate 53 is arranged as a protection for the head. This plate may be connected by means of two rivets 55, to a metal plate 51. A slit 54 in the latter admits the hair strand into a central aperture in the plate. The plate 53 has for the same purpose a slit 34 which is arranged at right angles to the slit 54. The part 56 confined by the slits 34 is free to be opened out for admitting the hair strand into the central apertures of the interconnected plates. One edge 40 of the plate 51 is turned up so as to form a gutter 52 wherein water of condensation which happens to leak through from between the clamping plates can be caught.

The plate 51 may be omitted in which case 50 the gutter 52 is replaced by an absorptive pad 57 (Figs. 12 and 13) of sponge rubber or the like.

I claim:

1. A hair waving appliance comprising a 55 flat cylindrical steam distributing chest having a domed top plate and a steam inlet disposed centrally in said plate, uniformly spaced outlet pipes connected to the circumference of said chest, a valve in each outlet 60 pipe, and means for connecting hair wavers to the pipes, the bottom wall of said chest being extended so as to form a gutter for the retention of water of condensation.

2. The structure claimed in claim 1 in 65 combination with a steam generator, an abruptly

bent pipe connecting said generator with the chest, and a spherical enlargement on said pipe arranged above and close to the generator so as to retain and return discharged water.

3. The structure claimed in claim 1 in combination with hair wavers each comprising a pair of hingedly connected, butted hair clamping plates, a neck on said plates arranged so as to embrace the hair, a hair steaming sleeve, a flexible connection between said sleeve and the neck, means for connecting said sleeve to one of the outlets of the steam chest, and a hair coiling rod connected to one of the clamping plates so 70 as to be enclosed in said sleeve.

4. The hair waving apparatus comprising a pair of hingedly connected, butted hair clamping plates, segmental shells connected to said plates so as to form together a neck, 75 when the plates are closed, a hair steaming sleeve, a flexible connection between said sleeve and the neck, a hair coiling rod connected to one of said plates within the shell so as to allow of being enclosed in said sleeve, 80 and means for supplying steam to and discharging it from the sleeve.

5. A structure as claimed in claim 4 wherein the ends of the shell of one plate are extended beyond the edge of said plate. 85

6. The structure claimed in claim 4 in combination with a lever clasp for clamping the plates together about the hair.

7. A structure as claimed in claim 4 wherein the abutting edges of the plates are 100 slightly concave.

8. The structure claimed in claim 4 in combination with a U-shaped rubber covers adapted to be slipped over the abutting edges of the plates, the covers being formed 105 with slits for the reception of the shells.

9. The structure claimed in claim 4 in combination with an insulating plate adapted to be interposed between the clamping plates and the head, and means on said insulating plate for retaining water of condensation. 110
